UNITED STATES PATENT OFFICE.

JOSEPH DEL RE, OF CHICAGO, ILLINOIS.

UMBRELLA.

1,282,387.

Specification of Letters Patent. Patented Oct. 22, 1918.

Application filed April 9, 1918. Serial No. 227,471.

To all whom it may concern:

Be it known that I, JOSEPH DEL RE, a citizen of the United States, and a resident of the city of Chicago, county of Cook, and 5 State of Illinois, have invented certain new and useful Improvements in Umbrellas, of which the following is a specification.

My invention relates to improvements in umbrellas, and has for its object the production 10 of a device of this character, which will be of durable and economical construction, and efficient in use.

Other objects will appear hereinafter.

The invention consists in the combinations 15 and arrangements of parts hereinafter described and claimed.

The invention will be best understood by reference to the accompanying drawings forming a part of this specification, and in 20 which,

Figure 1, is a top plan view of an umbrella in open condition, embodying the invention, a portion of the cover of the umbrella being broken away to expose underlying parts,

Fig. 2, a substantially central section through the umbrella, in open condition,

Fig. 3, a substantially central section of the umbrella in closed condition,

Fig. 4, an enlarged sectional detail of the construction as seen in Fig. 3, and

Fig. 5, an enlarged detail perspective view of the construction as seen in Fig. 2.

The preferred form of construction as 35 illustrated in the drawings comprises a tubular stick 6 provided at one end with a suitable handle 7. Pivotally connected at 8 with the other end of the stick 6 is a plurality of radially disposed ribs 9, to which 40 is fastened, in the usual manner, a fabric cover 10. Coöoperating with ribs 9 are spreaders 11, the outer ends of which are pivotally connected with said ribs at 12, the inner ends of said spreaders being pivotally 45 connected at 13 with a tubular runner 14 shiftably mounted upon stick 6.

Coöoperating with the runner 14 in order 50 to hold the umbrella ribs in spread or open position, is a pawl 15 arranged in the stick 6 and pivotally connected therewith at 16. A leaf spring 17 coöperates with said pawl to normally hold the same in operative position. The arrangement is such, as will be seen, that said pawl is adapted automatically 55 to engage with the end of the runner 14 when the umbrella is opened in order to lock the same in this condition.

In order to lock the umbrella in closed condition, a pawl 18 is provided in the stick 6 adjacent the other end thereof, said pawl 60 being pivotally secured to the stick by a pin 19. Said pawl is provided with an elongated slot 20 which is engaged by the pin 19, the arrangement being such that said pawl will be permitted both pivotal and 65 shifting movement. A leaf spring 21 co-operates with said pawl to normally hold the same in outward or operative position. Formed in the runner 14 adjacent one end 70 thereof is an annular internal groove or shoulder 22, which is adapted, when the umbrella is in closed condition, to be engaged by the pawl 18, as clearly seen in Fig. 4, whereby the umbrella is locked in this condition.

Operation of the pawls 15 and 18 is effected by means of an extension or finger piece 23 provided upon the pawl 18, said member 23 projecting exteriorly adjacent the handle 7 of the umbrella so as to permit of ready 80 engagement thereof by the thumb of the user. The arrangement is such that through depression of said member 23 the pawl 18 will be moved inwardly to releasing position in order to release the runner 14 and 85 permit of opening of the umbrella. The inner end of pawl 18 is connected by a wire or other suitable connecting element 24 with the pawl 15, so that through shifting of the member 23 toward the handle 6 said pawl 90 15 will be retracted and thus the runner 14 released in order to permit of closing of the umbrella. With this arrangement then, it will be seen that the member 23 affords means of manual operation of both pawls 95 of the umbrella in either opening or closing the latter.

Coöoperating with each rib 9 is a pair of laterally flexible resilient bars 25, the outer ends thereof being pivotally connected with 100 the corresponding rib 9 at the point 12, the inner ends of said bars being pivotally connected at 26 with a runner 27 which is slidably mounted upon the runner 14. The outer ends of the bars 25 of each pair thereof are securely fastened together by a band 28 which embraces the same, as clearly seen in Fig. 5. The inner ends of adjacent bars of adjacent pairs thereof are secured together by bands 29, as clearly seen in Fig. 110 1. The arrangement is such that when the umbrella is closed, the bars 25 will be in normal straight condition. Upon movement of the ribs 9 from closed position, said

bars 25, due to the connection between the adjacent pairs thereof, will be flexed laterally, as clearly seen in Fig. 1, thus being placed under tension. This being so, when 5 the umbrella is in fully opened condition the bars 25 will be under maximum tension, constantly exerting pressure tending to close the umbrella. Therefore, upon release of the runner 14, through retraction 10 of pawl 15, the bars 25 will operate to effectually and instantly swing the ribs 9 to closed position and serve to retain said ribs in this fixed position even though the pawl 18 should fail to operate, that is, to engage with the stop shoulder 22.

While I have illustrated and described the preferred form of construction for carrying my invention into effect, this is capable of variation and modification without departing 20 from the spirit of the invention. I therefore, do not wish to be limited to the precise details of construction set forth, but desire to avail myself of such variations and modifications as come within the scope of 25 the appended claims.

Having described my invention, what I claim as new and desire to secure by Letters Patent is:—

1. An umbrella comprising a stick; ribs 30 pivotally connected with said stick; means for yieldingly holding said ribs in a fixed position, said means comprising spreaders connected with said ribs, a pair of elongated flexible bars coöperating with each of said 35 ribs; and an operative connection between adjacent bars of adjacent pairs thereof, substantially as described.

2. An umbrella comprising a stick; ribs pivotally connected with said stick; means 40 for yieldingly holding said ribs in a fixed position, said means comprising spreaders connected with said ribs, a pair of elongated flexible bars coöperating with each of said ribs and having their outer ends connected thereto; a sliding connection between the inner ends of said bars and said stick; and an operative connection between adjacent 45 pairs of said bars, whereby said bars are laterally flexed when said ribs are moved from said fixed position, substantially as described.

3. An umbrella comprising a stick; ribs pivotally connected with said stick; means 55 for yieldingly holding said ribs in a fixed position, said means comprising spreaders connected with said ribs, a pair of elongated flexible bars coöperating with each of said ribs and having their outer ends connected thereto; a sliding connection between the 60 inner ends of said bars and said stick, the bars of each pair of bars being secured together at one end; and an operative connection between adjacent bars of adjacent

pairs thereof, whereby said bars are laterally flexed when said ribs are moved from 65 said fixed position, substantially as described.

4. An umbrella comprising a stick; ribs pivotally connected with said stick; means 70 for yieldingly holding said ribs in a fixed position, said means comprising spreaders connected at their outer ends with said ribs; a runner slidably mounted on said stick with which the inner ends of said spreaders are connected, a pair of elongated flexible 75 bars coöperating with each of said ribs and having their outer ends connected thereto; a runner slidably mounted on said first mentioned runner and to which the inner ends of said bars are connected, the bars of each 80 pair of said bars being secured together at one end; and an operative connection between the opposite ends of adjacent bars of adjacent pairs thereof, whereby said bars are laterally flexed when said ribs are moved 85 from said fixed position, substantially as described.

5. An umbrella comprising a stick; ribs pivotally connected with said stick; means 90 for locking said ribs in either spread or closed position, said means comprising a pair of stop pawls arranged in said stick adjacent the ends thereof; and a manually operable element provided on said stick for operating both of said pawls, substantially 95 as described.

6. An umbrella comprising a stick; ribs pivotally connected with said stick; means 100 for locking said ribs in either spread or closed position, said means comprising a pair of stop pawls arranged in said stick adjacent the ends thereof; and a pivotally and slidably mounted operating element provided upon said stick for operating both of said pawls, substantially as described. 105

7. An umbrella comprising a stick; ribs pivotally connected with said stick; means 110 for locking said ribs in either spread or closed position, said means comprising a pair of stop pawls arranged in said stick, adjacent the ends thereof; a pivotally and slidably mounted operating element provided upon said stick; and an operative connection between said element and said pawls, whereby, upon pivotal movement of said element, one of said pawls will be operated, and upon shifting movement of said element the other of said pawls will be operated, substantially as described.

In testimony whereof I have signed my 120 name to this specification in the presence of two subscribing witnesses.
